(57) **CLAIM**

The ornamental design for a pair of glasses with bone conduction earphones, as shown and described.

DESCRIPTION

FIG. 1 is a perspective view of a pair of glasses with bone conduction earphones showing our new design, in an unfolded configuration, under a first embodiment;

FIG. 2 is another perspective view of the pair of glasses with bone conduction earphones, in the unfolded configuration, under the first embodiment;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a perspective view of a pair of glasses with bone conduction earphones showing our new design, in a folded configuration, under the first embodiment;

FIG. 10 is another perspective view of the pair of glasses with bone conduction earphones, in the folded configuration, under the first embodiment;

FIG. 11 is a front view thereof;

FIG. 12 is a rear view thereof;

FIG. 13 is a left view thereof;

FIG. 14 is a right view thereof;

FIG. 15 is a top view thereof; and

FIG. 16 is a bottom view thereof.

FIG. 17 is a perspective view of a pair of glasses with bone conduction earphones showing our new design, in an unfolded configuration, under a second embodiment;

FIG. 18 is another perspective view of the pair of glasses with bone conduction earphones, in the unfolded configuration, under the second embodiment;

FIG. 19 is a front view thereof;

FIG. 20 is a rear view thereof;

FIG. 21 is a left view thereof;

FIG. 22 is a right view thereof;

FIG. 23 is a top view thereof;

FIG. 24 is a bottom view thereof.

FIG. 25 is a perspective view of a pair of glasses with bone conduction earphones showing our new design, in a folded configuration, under the second embodiment;

FIG. 26 is another perspective view of the pair of glasses with bone conduction earphones, in the folded configuration, under the second embodiment;

(Continued)

FIG. 27 is a front view thereof;
 FIG. 28 is a rear view thereof;
 FIG. 29 is a left view thereof;
 FIG. 30 is a right view thereof;
 FIG. 31 is a top view thereof; and,
 FIG. 32 is a bottom view thereof.

The shade lines in the figures show contour and not surface ornamentation.
